DIPPER TRIP MECHANISM

Raymond A. Beckwith, Milwaukee, Wis., assignor
to Koehring Company, Milwaukee, Wis., a cor-
poration

Application August 1, 1944, Serial No. 547,533

3 Claims. (Cl. 214—146)

My present invention pertains to the art of excavating machines, and particularly to the type of these machines known as power shovels or excavators, in which a dipper, usually mounted upon a dipper stick, is mounted for excavating work. In machines of this class the dipper is equipped usually with a drop bottom adapted to be unlatched or unlocked by the operator of the machine in order to discharge the contents of the dipper.

My invention comprises novel mechanism known in the art as dipper trip mechanism for performing the function of unlatching or discharging the contents of the dipper by opening the bottom thereof in the customary manner.

My dipper trip mechanism has been designed with a special view of obtaining reliability of operation and enabling the dipper trip function to be performed by very slight physical exertion incident to finger pressure upon a controlling operating member conveniently arranged upon one of the main operating levers, in the present instance the crowd lever of the machine. Since the trip latch of the dipper is obviously resisting a heavy load or pressure incident to the dirt or material received in the dipper, when holding the door against the opening movement thereof, it is very important that a power trip arrangement of the type of my arrangement be slow but positive in its initial pull on the trip mechanism, a mode of functioning accomplished by means of my improved mechanism. While the starting movement of tripping the dipper latch is slow, the instrumentalities which I provide afford an accelerated motion just after the manual initiation of the tripping operation is started.

In carrying out my invention, the operation of tripping of the dipper or bucket latch is accomplished entirely by mechanical power in so far as the power applied for moving the latch is concerned, and this of course does not necessitate any physical exertion on the part of the operator of the excavating machine.

Various advantages of my mechanical construction of the means for tripping the dipper for opening and discharging action thereof will be fully apparent upon reference to the following description in conjunction with the accompanying drawings, in which:

Figure 1 is a side elevation of the body and boom portions of an excavating dipper or shovel of generally conventional type, the illustration being somewhat fragmentary and the general operating instrumentalities for the dipper trip mechanism being shown.

Figure 2 is a fragmentary side view showing more clearly the arrangement for mounting of the tripping pawl or dog which works in conjunction with the toothed wheel and the control lever for said pawl or dog.

Figure 3 is a sectional view bringing out more clearly the arrangement of the parts of the tripping mechanism itself, certain parts being broken away, taken on line 3—3 of Figure 4.

10 Figure 4 is a side elevation of the members primarily as illustrated in Figure 3.

Figure 5 is a perspective view of the crank lever, dog, and supporting means for the latter.

15 Figure 6 is a view of the dog and its carrying sleeve and arm support, detached to show the construction clearly.

Describing my improvements in detail, and referring to Figure 1 of the drawings particularly, I note that the body of the shovel or excavating 20 means is illustrated at A and is a conventional type of body intended to contain the main operating mechanism of the machine and having a platform or cab in which the operator stands.

On the body A is carried the customary crowd 25 lever designated 20 and at the upper end of this lever is the depressible or movable fingerpiece 1. The member 1 is connected by a rod 2 and by means of crank levers and suitable linkage 3 to a crank lever 4 disposed adjacent the trip mechanism unit, for a purpose to be later described. The above simple arrangement of parts comprises the operating devices leading from the lever 20 which is pivoted at 20a to the trip unit carried somewhat rearwardly of the machine as located 35 in reference to the lever system including the lever 20.

Now from the trip unit which is generally designated B in Figure 1, and adjacent to which the crank lever 4 previously referred to is disposed, 40 there lead certain operating parts which pass to the latch on the dipper of the machine, and which latch is tripped in order to open the bottom of the dipper and discharge its contents. Figure 1 illustrates these operating parts as including a trip cable 11 that leads to the dipper along the boom 15. The boom 15 carries the customary dipper stick and dipper on said stick according to well known arrangement used today. The cable 11 is connected by levers 12 on a suitable

45 axis support 12a to an operating line or cable 13 which in turn is connected to a bell crank lever and linkage system 14, the latter directly connected with the trip crank 10 of the trip unit B.

50 I next pass to an explanation of the details of the trip mechanism which is shown best in Fig-

ures 2, 3, and 4 of the drawings. As seen in Figure 3, there is provided a constantly rotating shaft 16, and to the outer end of this shaft 16 is bolted or otherwise secured a toothed wheel or member 1, the attachment bolts of which are designated 7a.

Supported in the central portion of the wheel 1 as an inner bearing is a normally non-rotating shaft 9. To provide an outboard bearing for the shaft 9 there is employed a housing or spider member 18. Keyed or otherwise secured to the shaft 9 is sleeve 22 constituting the supporting part of a pawl supporting crank having two crank arms 8. The sleeve 22 may be additionally affixed to the shaft 9 by means of the clamp bolt 23. The arms pivotally carry a pawl or dog 6 mounted upon the small axis shaft 26 having bearing in the arms 8 by means of a sleeve part 28 which spans the space between the members 8. Encircling this sleeve part designated 28 is a coiled or helical spring 27, one end of which is anchored and the other end of which engages pin 29 laterally projecting from the pawl or dog 6.

The normal action of the spring 27 will be apparent by reference to Figure 4.

Under normal non-operating conditions of the trip mechanism a roller 5 on the bell crank lever 4 is so positioned as to be located beneath the pawl 6 in contact therewith, thereby holding the pawl in a slightly upraised condition in which it is not engaged with the teeth of the toothed member 7.

The trip crank 10 previously mentioned is welded, keyed or otherwise secured to the outer end of the shaft 9 and is operated by said shaft to turn rotatively when the dog or pawl 6 has become engaged with the toothed member 7, whereby to initiate a pull upon the connections that lead to the dipper latch for the opening or movement of the latter in discharging the dipper.

With the above construction of my general mechanism in mind, the general operation of the trip means is as follows:

It will be assumed that the dipper of the excavator has been operated to engage with the earth and become loaded with the materials to be excavated, the loading operation of course being effected under the control of the crowd lever 20 and other suitable levers of the lever stand in the body A of the machine. It will be further assumed that the dipper stick has been operated to raise the dipper and the excavator body has been swung, we will say, to carry the dipper over a vehicle to receive the load of material discharged from the dipper or to discharge the material onto some other place of deposit.

When the dipper has been disposed in its discharging position, the operator, simply by finger touch or movement, depresses the fingerpiece 1 of the lever 20. This action results in operating the parts 2, 3, and 4 whereby to bring the roller 5 of the crank lever 4 out of engagement with the underside of the pawl or dog 6. This results in the downward or dropping movement of the pawl under the action of the spring 27, so the pawl, previously not engaged with the teeth of the toothed member 7, will be caused to engage one of these teeth while the member 7 is rotating under the constant rotative effort of the main shaft 16. The engagement of the pawl 6 with the toothed wheel 1 causes the arm or crank 8, keyed to the shaft 9, to be picked up, thereby imparting rotation to the shaft 9 along with its secured crank member 10. While the members 8 and 10 are making one revolution, a sufficient

movement is imparted to the members 14, 13, 12, and 11 to pull the latch which secures closed the bottom of the dipper out of its latching position to its released position and thereby effecting dumping or discharging of the contents of the dipper. While the cranks 8 and 10 are making one revolution the operator removes his finger from the push pin or fingerpiece 1, allowing the bell crank and other connections to the crank 4 to return to their former position thereby placing the roller 5 in the path of the pawl 6 again, so that when the pawl comes in contact with the roller 5 in the revolution of the toothed member 7 the pawl 6 will be automatically disengaged from the teeth of the toothed member 7, in an obvious manner.

The contact pressure between the pawl 6 and the wheel 7 at the time of the disengagement is very low due to the vertical position of the cranks 8 and 10 and rod 14 attached to the crank 10.

If the operator fails to remove his finger pressure on the member 1, it will be apparent that the pawl 6 will remain in engagement with the toothed member 7, simply re-tripping the dipper trip latch of the excavator intermittently until the finger pressure on the member 1 is removed. The above action does not perform any useful function, and of course the excavator operator will remove his finger pressure as soon as he sees he cannot keep the bottom door closed in relation to the dipper structure, by maintaining such pressure.

The shaft 16 is designed to be either a drum shaft end or the end of a swing shaft, each of which is always found in a shovel dipper of the construction to which my invention pertains. However it is within the purview of my invention that the shaft 16 may be any shaft that operates at a suitable constant speed such as that of the swing shaft for instance. The toothed member 7 is bolted to the facing end of the shaft 16 as previously described, and in the present construction illustrated said member acts as a ball bearing clamp. The part 17 is a ball bearing housing to which is bolted the supporting or spider member 18 for the outer end of the shaft 9.

Figure 2 shows the roller 5 in the position assumed thereby to allow the pawl 6 to drop into engagement with the member 7. A split bearing cap 19 is employed as a means for supporting a housing 17 and member 18 in the manner above described.

While the fingerpiece or pin 1 is located within the grip of the crowd lever 20 for convenience of thumb operation it is apparent that this member 1 might be disposed in any suitable position near the operator for easy reach by him irrespective of mounting the same upon a lever such as the crowd lever previously described.

When pawl 6 is disengaged by abutment with the roller 5 as previously described, the upward movement of the pawl causes it to strike a stop 22a on the crank arm sleeve 22, thereby also stopping rotation of the pawl and parts operated thereby, notably the shaft 9, crank 10 and connected parts.

Having thus described my invention, what I claim as new and desire to secure by Letters Patent of the United States is:

1. In dipper trip mechanism, a trip unit comprising, in combination, a constantly rotating shaft, an internally toothed wheel fixed to said shaft, a normally stationary trip shaft coaxial with the said first shaft, a pawl supporting crank fixed to the trip shaft, a trip crank also fixed to

the trip shaft, a pawl pivotally carried by the supporting crank aforesaid, and arranged to engage with the teeth of the toothed wheel, a lever normally engaging the pawl to prevent engaging of the latter with the toothed wheel, and means to move said lever to release the pawl for engaging the toothed wheel for causing actuation of the pawl supporting and trip cranks.

2. Mechanism as claimed in claim 1, in which the wheel engaging portion of the pawl operates within the toothed part of the wheel, and a spring encircling the axis of the pawl normally tending to engage same with the toothed wheel. 10

3. Mechanism as claimed in claim 1, in which the wheel engaging portion of the pawl operates within the toothed part of the wheel, and a spring encircling the axis of the pawl normally tending to engage same with the toothed wheel, the toothed wheel being coaxial with and attached to an end of the constantly rotating shaft, a fixed bearing for said constantly rotating shaft, and a spider carried by said bearing and extending outwardly therefrom and provided with an outboard bearing spaced from the wheel and receiving the outer end of the normally stationary shaft.
